(57) **CLAIM**

I claim the ornamental design for an extendable capacitive stylus, as shown and described.

DESCRIPTION

FIG. 1 is a side elevation and front perspective view of the extendable capacitive stylus, shown fully extended;

FIG. 2; is a side elevation and front perspective view of the extendable capacitive stylus, shown partially extended;

FIG. 3 is a side elevation and front perspective view of the extendable capacitive stylus, shown fully closed;

FIG. 4 is a side elevation view of the extendable capacitive stylus, shown fully closed, wherein the opposite side is a mirror image of same;

FIG. 5 is a side elevation view of the extendable capacitive stylus, shown partially extended, wherein the opposite side is a mirror image of same;

FIG. 6 is a side elevation view of the extendable capacitive stylus, shown fully extended, wherein the opposite side is a mirror image of same;

FIG. 7 is a top plan view of the extendable capacitive stylus;

FIG. 8 is a bottom view of the extendable capacitive stylus;

FIG. 9 is a front view of the extendable capacitive stylus, shown fully closed;

FIG. 10 is a front view of the extendable capacitive stylus, shown partially extended;

FIG. 11 is a front view of the extendable capacitive stylus, shown fully extended;

FIG. 12 is a rear view of the extendable capacitive stylus, shown fully closed;

FIG. 13 is a rear view of the extendable capacitive stylus, shown partially extended; and,

FIG. 14 is a rear view of the extendable capacitive stylus, shown fully extended.
